DESIGN FOR A TEXTILE FABRIC

Peter S. Schwartz, New York, N. Y.

Application January 22, 1941, Serial No. 98,278

Term of patent 3½ years

To all whom it may concern:

Be it known that I, Peter S. Schwartz, a citizen of the United States residing at 2165 Bolton Street, in the county of Bronx and State of New York, have invented a new, original, and ornamental Design for Textile Fabric, of which the following is a specification, reference being had to the accompanying drawing, forming a part thereof.

The figure on the drawing is a plan view of a textile fabric showing my new design.

I claim:

The ornamental design for a textile fabric, as shown.

PETER S. SCHWARTZ.
